(57) **CLAIM**

The ornamental design for an ignition controller for engines, as shown and described.

DESCRIPTION

FIG. 1 is a front perspective view of the ignition controller for engines showing our new and ornamental design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1; and,

FIG. 8 is a rear perspective view of FIG. 1.

The portions of the ignition controller for engines shown in broken lines in the figures attached hereto form no part of the claimed design.
